Filed May 15, 1962, Ser. No. 70,140

Term of patent 14 years

(Cl. D91—1)

Fig. 1.

Fig. 2

Fig. 3

Fig. 4.

FIG. 1 is a side elevational view of a spray nozzle showing my new design the opposite side thereof being substantially the same in appearance;

FIG. 2 is a side elevational view thereof as viewed from the right in FIG. 1, the opposite side thereof being substantially the same in appearance;

FIG. 3 is a top plan view thereof;

FIG. 4 is a bottom plan view thereof.

The characteristic features of my design reside in that portion of the spray nozzle above the hexagonal element, which portion consists of a substantially cylindrical portion with two shallow opposing planar surfaces, a flat top with chamfered edges and a diametrically positioned V-shaped slot circumscribing a lenticular shaped aperture, as shown.

I claim:

The ornamental design for a spray nozzle substantially as shown and described.
